US00D977300S

(12) **United States Design Patent** (10) **Patent No.:** **US D977,300 S**
(45) **Date of Patent:** **** Feb. 7, 2023**

(54) **LID**

(71) Applicant: **TAIZHOU GUANGHANG E-COMMERCE CO., LTD.**, Taizhou (CN)

(72) Inventor: **Wenhui Shi**, Taizhou (CN)

(73) Assignee: **TAIZHOU GUANGHANG E-COMMERCE CO., LTD.**, Taizhou (CN)

(**) Term: **15 Years**

(21) Appl. No.: **29/802,239**

(22) Filed: **Aug. 4, 2021**

(30) **Foreign Application Priority Data**

Jul. 15, 2021 (CN) 202130449004.9

(51) **LOC (14) Cl.** **07-01**

(52) **U.S. Cl.**

USPC **D7/392.1**

(58) **Field of Classification Search**

USPC D7/392, 392.1, 396.1, 396.2, 397, 509, D7/510, 533, 619.1, 622; D9/435, 443, D9/447, 449, 516

CPC B65D 43/0225; B65D 47/122

Primary Examiner — Kendra Leslie Hamilton

(57) **CLAIM**

The ornamental design for a lid, as shown and described.

DESCRIPTION

FIG. 1 is a perspective view of a lid showing my new design; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and, FIG. 8 is a bottom plan view thereof.

The broken lines in the drawings depict portions of the lid that form no part of the claimed design.

1 Claim, 8 Drawing Sheets
